P. W. POMEROY.
VEHICLE BODY.
APPLICATION FILED MAY 23, 1917.

1,301,005.

Patented Apr. 15, 1919.

UNITED STATES PATENT OFFICE.

PERCY W. POMEROY, OF TOLEDO, OHIO, ASSIGNOR TO THE WILLYS-OVERLAND COMPANY, OF TOLEDO, OHIO.

VEHICLE-BODY.

1,301,005.

Specification of Letters Patent. Patented Apr. 15, 1919.

Application filed May 23, 1917. Serial No. 170,445.

To all whom it may concern:

Be it known that I, PERCY W. POMEROY, a citizen of the United States, residing at Toledo, in the county of Lucas and State of Ohio, have invented certain new and useful Improvements in Vehicle-Bodies, of which I declare the following to be a full, clear, and exact description.

This invention relates to convertible bodies for motor vehicles, and more particularly to convertible bodies having door and window pillars which are completely removable to convert from a closed to an open car.

The principal object of this invention is to provide an improved removable pillar construction having detachable connections with the top and body, and locking and tensioning means intermediate the detachable connections. Another object is to provide a removable pillar comprised of a plurality of sections and locked and tensioned against both vertical and horizontal movement. Another object is to provide an improved removable pillar construction having separable engaging and locking means whereby the pillar may be secured to the body and top quickly, and then locked under tension. Another object is to provide a removable pillar construction such that, when the vehicle is converted into the open type, the parts fixed to the top and body may be covered by the upholstery, leaving no exposed parts.

Further objects, and objects relating to economies of manufacture and details of construction, will definitely appear from the detailed description to follow:

I accomplish the objects of my invention by the devices and means described in the following specification: My invention is clearly defined and pointed out in the appended claims.

A structure constituting a preferred embodiment of my invention is illustrated in the accompanying drawing, forming a part of this specification, in which:

Figure I is a side elevation of a motor vehicle body in which my invention is embodied;

Fig. II is an enlarged, fragmentary, sectional view taken substantially on line II-II of Fig. I showing the detachable connections at the ends of the pillar sections and the locking and tensioning means intermediate said ends;

Fig. III is an enlarged, sectional view, taken on line III-III of Fig. II, showing the locking means;

Fig. IV is an elevational view, looking in the direction of the arrow in Fig. III, showing the eccentric locking member;

Fig. V is a blank of the keeper;

Fig. VI is an enlarged, sectional view, similar to the lower portion of Fig. II, showing the pillar and connection before it is placed under tension;

Fig. VII is a perspective view of the resilient tongue portion of the detachable connection;

Fig. VIII is a perspective view of the angle plate forming part of the detachable connection;

Fig. IX is a sectional view showing a modified form of locking means;

Fig. X is a sectional view taken on line X-X of Fig. IX;

Fig. XI is a sectional view taken on line XI-XI of Fig. IX; and

Fig. XII is a perspective view of the angle plate forming part of the locking means.

In the drawings, similar reference characters refer to similar parts throughout the several views and the sectional views are taken looking in the direction of the little arrows at the ends of the section lines.

Considering the numbered parts of the drawing, 1 represents the body of the motor vehicle, and 2 the permanent top. The removable or demountable pillars comprise upper and lower sections 3 and 4, which are detachably connected at their ends to the body 1, and the permanent top 2, respectively, and serve as guides for the edges of the windows 5, as shown in Fig. I. When it is desired to convert the closed vehicle, shown in Fig. I, into a vehicle of the open type, the windows 5 are lowered into the body and the pillar sections are released and disconnected from the top and body, respectively, and are entirely removed.

The detachable connections being the same at the top and the bottom, for convenience, I will describe only the connections at the top. A plate 6 is secured by screws 7 to the top of the pillar section 3. The plate 6 has a resilient tongue portion 6' and an out-turned lug 8, the lug 8 being adapted to engage in a slot 13 of an angle plate 9. The angle plate 9 is secured to the inner edge and under side of the top 2 by screws 10 and 110

an upturned edge 11. The plate 9 has a slot 12 at its angle through which resilient tongue portion 6' of the plate 6 may extend. As the tongue portion 6' of the plate 6 is extended through the opening 12 of the angle plate 9, the outturned lug 8 engages the slot 13, and, to secure the pillar under tension, an edge 14 of the angle plate 9 presses against the inner side of the plate 6, 10 while the body portion of the plate 9 between the slots 12 and 13 engages the other side of the resilient plate 6, the parts arranged to tension the pillar against lateral movement when the pillar sections are held 15 in vertical position. (See Figs. II and VI). To allow for the removal of the tongue portion 6' of the plate 6, a recess 15 is provided in the top 2.

To lock and tension the pillars against 20 both lateral and vertical movement, I provide a device for locking the inner ends of the sections 3 and 4 together and coöperating with the connection means between the sections and the body and top to draw the 25 sections together laterally and longitudinally to place them under tension. A recess 16 is provided in the upper end of the pillar section 4, in which is secured a cup 17 by screws 18. Mounted in the cup 17 30 is a spindle 19 having an operating handle 20 at its outer end. The spindle 19 is held against lateral movement by the shoulder 21 and the pin 22. Mounted on the spindle 19 is an eccentric latch 23, the same being 35 secured by a pin 26. The inner side of the face 24 of the latch 23 is adapted to engage the keeper member to be hereinafter described. The edges 25 of the face 24 are wedge-shaped and are adapted to engage the 40 keeper member to secure the pillar against lateral movement. The pillar section 3 is recessed at 27 to receive a keeper member 28, secured by screws 29. The upturned ends 30 of the keeper 28 have curved edges 31 and 45 are adapted to be engaged by the inner face 24 of the eccentric latch 23.

When it is desired to mount the removable pillar in place, the detachable connections between the pillar sections and the top 50 and body respectively are placed together in the manner indicated and the sections forced into place. The inner ends of the section when brought into alinement are secured together by a rotation of the spindle 55 19, the eccentric latch 23 being turned into engagement with the keeper member 28, and by means of the engagement between the plates 6 and 9 as described, and the action of the eccentric latch on the curved surfaces 60 31 of the keeper 28, together with the wedging action of the edges 25 of the latch against the sides of the keeper 28, the pillar sections are tensioned laterally and longitudinally and locked under tension.

65 In Figs. IX to XII, I have shown a

modified form of locking and tensioning device in which a recess 35 is formed in the pillar section 3 to receive a tapered socket 36. The socket 36 is adapted to receive a tapered pin 37. The tapered pin 37 has an enlarged head 38 which, when brought into locking engagement, rests on the underside of an angle bracket 39, secured to the upper end of the pillar section 4. The tapered pin 37 has a laterally extending arm 40, on which is slidably mounted an operating handle 41 and a tensioning cam 42. Secured to the inner face of the pillar section 3 is a slotted recessed member 43 which is adapted to receive the tensioning cam 42. When the pillar sections 3 and 4 are brought into alinement, the tapered pin 37 is pushed into the socket 36 with the smallest radius of the eccentric 42 being nearest pillar section 4. To draw the pillar sections longitudinally, 85 the operating handle is turned, and the engagement of cam 42 with member 43 thus draws the sections together. To hold the operating handle and cam against movement after the parts have been brought into 90 locked position, I provide holes 44 in the member 43, and a pin 45 on the eccentric 42, the pin 45 being adapted to engage in any one of the holes 44. To insure that the eccentric 42 will be held in engagement with 95 the member 43, a spring 46 is mounted on the arm 40, one end of which rests against the shoulder 47 of the operating handle 41, and the other against the head 48 of the extension arm 40. It will be noted that the 100 pillar sections 3 and 4 and connecting parts are slotted to allow for movement of the extension arm 40 and permit it to be lowered into the pillar section 4. The pillar section 4 is counterbored at 50 to receive the 105 tapered pin 37 when it is desired to drop the locking means into this section so that the pillar sections may be disengaged and the pillars removed from the body.

I am aware that the embodiment of my 110 invention here shown and described is susceptible of considerable variation without departing from the spirit of my invention and, therefore, I desire to claim the same broadly as well as specifically, as indicated 115 by the appended claims.

Having thus described my invention, what I claim as new and desire to secure by Letters Patent is:

1. In a vehicle, the combination of a body; 120 a top; a removable pillar comprising two sections; means for detachably connecting said pillar sections to said top and body respectively; and means for interlocking the inner ends of said pillar sections. 125
2. In a vehicle, the combination of a body, a top, a removable pillar comprising a plurality of sections, means for detachably connecting said pillar sections to said top and said body respectively, said means oper- 130

ating to permit tensioning of said pillar sections when in place, and means for interlocking the inner ends of said pillar sections.

5 3. In a vehicle, the combination of a body; a top; a removable pillar comprising two sections; engaging members secured to said sections and having each an outturned lug; plates secured to the top and body respectively and each having a slot adapted to detachably receive the outturned lug of the corresponding engaging member; and means for interlocking the inner ends of said pillar sections.

10 4. In a vehicle, the combination of a body, a top, a removable pillar comprising a plurality of sections, pillar connecting members secured to said sections, plates secured to the top and body respectively adapted to detachably receive said connecting members, said members and plates constructed to permit the tensioning of the pillar sections against lateral movement, and means for connecting said pillar sections.

15 5. In a vehicle, the combination of a body; a top; a removable pillar comprising two sections; means for detachably connecting said pillar sections to said top and body respectively; and means for interlocking and tensioning said pillar sections against both vertical and horizontal movement.

20 6. In a vehicle, the combination of a body; a top; a removable pillar comprising two sections; means for detachable connecting said pillar sections to said top and body respectively; a latch rotatably mounted in one of the pillar sections; and a keeper mounted in the other pillar section and engageable by said latch to interlock the inner ends of the pillar sections.

25 7. In a vehicle, the combination of a body; a top; a removable pillar comprising two sections; means for detachably connecting said pillar sections to said top and body respectively; an eccentric latch rotatably mounted in one of the pillar sections; and a keeper mounted in the other pillar section and engageable by the latch to draw the pillar sections together.

30 8. In a vehicle, the combination of a body; a top; a removable pillar comprising two sections; means for detachably connecting said pillar sections to said top and body respectively; an eccentric latch carried by one of said sections and having flanges at the edge thereof; and a keeper carried by the other section and having upturned edges engageable by said flanges.

35 9. In a vehicle, the combination of a body; a top; a removable pillar comprising two sections; means for detachably connecting

said pillar sections to said top and body respectively; an eccentric latch carried by one of said sections and having converging flanges; and a keeper carried by the other section and having upturned edges engageable by the inner face of said latch and sides engageable by the converging flanges of said latch, whereby, when the latch is turned to locking position, the pillar sections will be drawn together and tensioned against longitudinal and lateral movement.

40 10. In a vehicle, the combination of a body; a top; a two-part removable pillar, detachably connected to said top and body respectively; and means for locking said pillar in position, located intermediate the ends thereof.

45 11. In a vehicle, the combination of a body; a top; a removable two-part pillar; detachably connected to said top and body respectively; and means for locking said pillar in position and tensioning it against lateral and longitudinal movement, located intermediate the ends thereof.

50 12. In a vehicle, the combination of a body; a top; a removable two-part pillar, detachably connected to said top and body respectively; and means for interlocking the parts of said pillar.

55 13. In a vehicle, the combination of a body; a top; a removable two-part pillar; means resiliently and detachably connecting said pillar to said top and body respectively; and means for interlocking the adjacent ends of said pillar parts.

60 14. In a vehicle, the combination of a body, a top, a removable multiple-part pillar detachably connected to said top and said body respectively, and means for connecting the parts of said pillar.

65 15. In a vehicle, the combination of a body, a top, a removable multiple-part pillar detachably connected to said top and said body respectively, means for connecting the parts of said pillar, and means for tensioning said pillar against lateral movement.

70 16. In a vehicle, the combination of a body, a top, a removable pillar comprising a plurality of sections, pillar connecting members secured to said sections, said members being provided with an out-turned lug, slotted plates secured to the top and body respectively being adapted to detachably receive said connecting members with the lugs located within the slots, and means for connecting said pillar sections whereby the same are removably secured to said body and top under tension against lateral and longitudinal movement.

75 17. In testimony whereof I affix my signature.
PERCY W. POMEROY.
